United States Patent Office

Des. 187,559
Patented Mar. 29, 1960

187,559

BOTTLE

Willard R. Horne, Brooklyn, N.Y., assignor to The Procter & Gamble Company, Cincinnati, Ohio, a corporation of Ohio

Application November 21, 1958, Serial No. 53,476

Term of patent 14 years

(Cl. D58—8)

FIG.1.

FIG.2.

FIG.3.

The side not shown is the same as the side shown.
I claim:

The ornamental design for a bottle, as shown and described.
